UNITED STATES PATENT OFFICE.

JOHN GEORGE KOSTMAYER, OF NEW ORLEANS, LOUISIANA.

DESIGN FOR A BRANDING-IRON.

SPECIFICATION forming part of Design No. 17,021, dated December 7, 1886.

Application filed October 19, 1886. Serial No. 216,654. Term of patent 7 years.

To all whom it may concern:

Be it known that I, JOHN GEORGE KOSTMAYER, a citizen of the United States of America, residing at New Orleans, in the parish of Orleans and State of Louisiana, have invented and produced a new and original Design for Branding-Irons, of which the following is a specification, reference being had therein to the accompanying drawings, forming part thereof.

Figure 1 is a face or top view of my newly-designed branding iron. Fig. 2 is a view of handle attached to branding-iron when in a vertical position.

Heretofore branding-irons have been made which presented, when viewed as a top or face view, a jagged or lettered face. In my branding-iron the edge or rim extends entirely around the goose shaped figure, the center being either open or concave.

The leading feature of my design consists in a legless goose-shaped face or top surface. The rim or edge, as in Fig. 1, will come in contact with body of object desired to be branded.

A is the rim or edge of the branding-iron, 25 which is goose-shaped and legless in its appearance.

B is a circular portion, which projects until it is on a level with rim or edge of the branding-iron, representing an eye.

B² is a hook on end of branding-iron handle for holding same; C, the rod or handle.

D are braces joined to handle at E and on back of rim or edge F, showing back of rim or edge, which is similar in formation to A.

35 I claim—

The design for a branding-iron herein shown and described, the same consisting of the rim or edge A and projection B, representing a legless-shaped goose.

40 In testimony whereof I affix my signature in presence of two witnesses.

JOHN GEORGE KOSTMAYER.
